THERMAL CONVERSION OF HYDROCARBONS PROMOTED BY EXPLOSIVE ORGANIC NITROGEN COMPOUNDS

Carlisle M. Thacker, Highland Park, and Willis O. Folkins, Evanston, Ill., assignors to The Pure Oil Company, Chicago, Ill., a corporation of Ohio

No Drawing. Application March 14, 1942,
Serial No. 434,790

6 Claims. (Cl. 260—683)

1

This invention relates to thermal reactions of hydrocarbons and more specifically to means for more efficiently carrying out such reactions with the aid of reaction promoting agents whereby lower temperatures and shorter reaction periods may be employed or higher yields obtained under given reaction conditions than those required for the ordinary unpromoted reaction.

Various thermal hydrocarbon reactions are rather well known. The thermal treatment of high boiling hydrocarbons whereby to produce hydrocarbons of lower molecular weight such as gasoline, largely by scission of carbon-to-carbon bonds, is the basis of cracking processes. Similarly, normally gaseous hydrocarbons may be thermally treated to produce normally gaseous olefins and paraffins and also hydrocarbons of higher molecular weight through further reactions ordinarily referred to as polymerization. The proportion of such higher boiling hydrocarbons obtained in gas conversion processes is ordinarily rather small when the conversion is effected at low pressures, but may be materially increased through the use of higher pressures. Normally liquid hydrocarbons of gasoline boiling range obtained by such processes are ordinarily used as motor fuel and normally gaseous olefin hydrocarbons may be converted into motor fuel boiling range hydrocarbons by polymerization or employed for any one of several other well known uses.

It is known that thermal reactions of saturated and unsaturated hydrocarbons may be induced under conditions of temperature and time too mild to ordinarily effect the reactions in a desired degree, by means of catalytic materials which are not destroyed and which remain substantially unchanged throughout the course of the reactions. For example, the use of well known dehydrogenation catalysts such as promoted activated alumina will permit the dehydrogenation of saturated hydrocarbons to a much greater degree at a given temperature than can be effected by similar treatment of the hydrocarbons in the absence of the catalyst. Similar improved results may be obtained by the use of appropriate catalysts in cracking, polymerization, isomerization, alkylation and other well known thermal hydrocarbon conversion reactions. Such reactions, so long as they are effected only at temperatures above atmospheric, whether effected in the presence or absence of

2

catalysts, are within the scope of the term "thermal hydrocarbon conversion" as used herein.

This invention provides a different method of bringing about thermal hydrocarbon conversion reactions under milder conditions than those required for the ordinary unpromoted reactions or which increase the rate of conversion under a given set of reaction conditions. This is effected by the use of certain reaction promoting agents which when employed in admixture with the hydrocarbons either materially reduce the severity of the conditions required to produce a given yield of desired product, or under a given set of reaction conditions materially improve the yield of desired products obtained.

An object of this invention is to increase the rate of thermal conversion reactions of hydrocarbons.

Another object is to effect thermal conversion of hydrocarbons under milder conditions than those required for the ordinary unpromoted reactions.

Another object of this invention is to effect the cracking of petroleum hydrocarbons under lower temperature conditions than can ordinarily be employed to obtain substantial yields of decomposition products.

Still another object of this invention is to effect the alkylation of hydrocarbons at a higher rate than that ordinarily obtainable under a particular set of reaction conditions.

A further object of the invention is to convert gaseous hydrocarbons into unsaturated hydrocarbons and also into normally liquid hydrocarbons with higher yields than those ordinarily obtainable under a given set of reaction conditions.

Still another object of this invention is to provide a method of increasing the rate of conversion of normally gaseous hydrocarbons into lighter unsaturated hydrocarbons and also into normally liquid hydrocarbons by the use of reaction promoting agents and to obtain higher yields than are obtainable under the same conditions in the absence of reaction promoting agents.

Other objects of the invention will be apparent as the description proceeds.

It has now been found that the thermal conversion of hydrocarbons may be promoted by organic nitrogen compounds which are decomposable under conversion conditions into decompo-

sition products which are in the same phase as the hydrocarbons undergoing conversion. The nature of the organic nitrogen compounds may vary widely. Those organic nitrogen compounds which contain only the elements carbon and hydrogen in addition to the nitrogen such as hydrocarbon amino compounds, are particularly effective. Hydrocarbon nitro compounds (not including the isomeric nitrites) have also been found to possess unusual merit. Among the hydrocarbon nitro compounds which may be used are nitromethane, dinitromethane, trinitromethane, tetrinitromethane, nitroethane, 1-nitropropane, 2-nitropropane and nitrobenzenes. Of these compounds, nitromethane has been found to be unusually efficacious. Examples of suitable hydrocarbon amino compounds are dimethylamine, triethylamine, diethylamine, trimethylamine, tripropylamine, mono-, di-, and triallylamine, di-n-propyl, di-iso-propyl- and isopropylamine. Of these amino compounds triethylamine has been found to be unusually effective. Organic compounds which decompose with explosive violence are particularly effective in aiding in the cracking of hydrocarbons containing 3 or more carbon atoms per molecule. The compounds which may thus be used are those compounds which are ordinarily referred to as high explosives such as nitroglycerin, trinitrotoluene, trinitroethylene, tetryl, picric acid, cellulose hexanitrate, nitromannite and others. The reason for this unusual effect of the explosive compounds is not known at the present time although it is thought that the shock of the decomposition of the explosive is communicated to the intimately associated hydrocarbon molecules undergoing decomposition, thus facilitating scission of the carbon to carbon bonds.

The thermal reactions which may be promoted as previously described may be conducted under varying conditions of time, temperature and pressure. In general, cracking reactions are effected under conditions of relatively low super-atmospheric pressure when the production of hydrocarbons of lower molecular weight is desired. However, the reaction may be conducted at relatively high pressures, particularly when the materials charged to the process are normally gaseous hydrocarbons, whereby to produce hydrocarbons of higher molecular weight than those charged to the process. The conditions of time and temperature required for effecting the desired thermal reactions with the aid of the reaction promoting agents are less severe than the conditions required in the absence of the reaction promoting agents. The optimum conditions can be readily determined by experiment. The reaction promoting agents herein disclosed are

particularly effective in facilitating the cracking of hydrocarbons having 3 or more carbon atoms per molecule. Ordinarily, the reaction promoting agents are employed in relatively small amounts such as from about 0.25% to 3 mol% of the hydrocarbons undergoing conversion.

In order to demonstrate the effectiveness of the reaction promoting agents employed in this invention, numerous experiments were carried out under static conditions in which a hydrocarbon, preferably n-butane, was decomposed in a reaction chamber under conditions of elevated temperature and the degree and rate of decomposition measured by the analysis of the resultant products and the measurement of the rate at which pressure increase occurred. In order to obtain a comparison between the un-promoted and promoted reactions, similar experiments were carried out in the presence of various reaction promoting agents. The following is a description of the method employed:

A reaction chamber, provided with suitable heating elements, was evacuated to a pressure of the order of 10^{-3} mm. and a mixture of n-butane containing a definite amount of reaction promoting agent admitted to the reactor. The temperature of the reactor was maintained sufficiently high to effect a substantial degree of decomposition of the n-butane. After charging the mixture of n-butane and reaction promoting agent to the reactor maintained at suitable temperature, the time in minutes required for a given increase in pressure was determined. Mixtures of the reaction promoting agents diluted with appropriate amounts of oxygen-free nitrogen were similarly treated in order to measure the rate of pressure increase due solely to the reaction promoting agent. The increase in pressure due to the reaction promoting agent per se was determined as shown in Table I and was deducted from the increases in pressure noted when mixtures of the reaction promoting agent and butane were charged to the reactor. By this means it was possible to estimate the effect of the various reaction promoting agents on the rate of decomposition of the n-butane. Analysis of the conversion products in each case indicated the nature of the conversion products obtained as a result of the decomposition reactions. Table II shows the results obtained on a number of runs in which n-butane of 99% purity was decomposed at a temperature of 525° C. and at pressures slightly above atmospheric—i. e., about 800–900 mm. All of the runs up to and including run 74 were carried out in a steel reaction chamber fabricated from alloy steel containing 18% chromium and 8% nickel. All other runs were carried out in a Pyrex glass reaction chamber.

From the data presented in Table II it will be seen that the use of reaction promoting agents in accordance with this invention materially increased the rate of decomposition of butane when used in proportions of about 0.25 to 3 mol % at temperatures of 525° C. Note, for example, that the rate of decomposition of butane in run 59 was such that 22.8 minutes were required for a 25% increase in pressure on the reactor, whereas in run 60 which was made under the same conditions as run 59 but in which 1% of triethylamine was employed as a reaction promoting agent, the decomposition rate was much higher since the time required for 25% pressure increase on the reactor was only 10.89 minutes, or less than half the time required in run 59. Similar beneficial results were obtained in those runs in which trimethylamine, dimethylamine, nitro-methane, nitro-ethane and allyl amine were employed as the reaction promoting agents. In all cases substantial amounts of olefinic hydrocarbons were present in the conversion products.

While in the foregoing specific examples the reaction promoting agents were employed to aid the thermal decomposition of butane, it is to be understood that the reaction promoting agents may similarly be employed to effect other thermal hydrocarbon conversion reactions such as, for example, alkylation, the polymerization of unsaturated hydrocarbons and those reactions wherein the hydrocarbons undergo molecular rearrangement such as isomerization. It is apparent that many changes may be made in the details as set forth in the foregoing description without departing from the spirit and scope of the invention as set forth in the following claims.

We claim:

1. The method of promoting thermal cracking of hydrocarbons which comprises subjecting said hydrocarbons to cracking temperature in the presence of a small amount of nitroglycerin.
2. The process of cracking hydrocarbons containing 3 or more carbon atoms per molecule in a reaction zone at elevated temperature suitable for cracking, comprising introducing into the hydrocarbons in the reaction zone a small amount of high explosive selected from the group consisting of nitroglycerin, trinitrotoluene, trinitroxylen, tetryl, picric acid, cellulose hexanitrate and nitromannite.

3. Process in accordance with claim 2 in which the explosive is used in amounts of 0.25 to 3 mole percent based on the hydrocarbon.

4. The method of promoting thermal cracking of hydrocarbons which comprises subjecting said hydrocarbons to cracking temperature in the presence of a small amount of trinitrotoluene.

5. The method of promoting thermal cracking of hydrocarbons which comprises subjecting said hydrocarbons to cracking temperature in the presence of a small amount of trinitroxylen.

6. In a process for thermally cracking hydrocarbons containing 3 or more carbon atoms per molecule the step comprising increasing the rate of cracking under conditions at which un-promoted thermal cracking occurs at less than a desired rate by admixing with the hydrocarbons approximately .25-3 mole percent of an explosive nitrated benzene ring compound decomposable under said conditions into decomposition products which are of the same phase as the hydrocarbons undergoing cracking.
